UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPE OR MATRIX.

1,111,098.

Specification of Letters Patent. Patented Sept. 22, 1914.

Original application filed November 26, 1912, Serial No. 733,586. Divided and this application filed March 28, 1914. Serial No. 827,794.

To all whom it may concern:

Be it known that I, JOHN R. ROGERS, a citizen of the United States, residing at Brooklyn, in the county of Kings and State of New York, have invented certain new and useful Improvements in Type or Matrices, of which the following is a specification, reference being had therein to the accompanying drawing.

- 10 My invention relates to type or matrices, and more particularly to that kind employed in machines of the character illustrated in U. S. Letters Patent No. 436,532, to O. Mergenthaler. In machines of this class the 15 matrices are stored in a magazine, are released therefrom by the manipulation of finger keys, are assembled in line, and then presented to a mold wherein the slug or linotype is cast. After this, the matrices are delivered to a distributing mechanism which 20 restores the matrices to their proper places in the magazine from which they started. Generally speaking, as disclosed in said Letters Patent, or as employed in the commercial 25 linotype machine, the matrices are formed with distributing combinations, and with ears whereby they are supported in their passage through the machine. These 30 matrices vary in size according to the special characters they are intended to produce, and in the thicker ones the distributing combinations are ordinarily formed in a web of less thickness than that of the matrix body, and the supporting ears are similarly of less than 35 the body thickness. It has been customary to locate the web and ears at opposite sides of such thick matrices, the web at the rear side and the ears at the forward side, and while this arrangement is entirely satisfactory 40 for most purposes, it renders them disadvantageous for others. In the present instance, therefore, I have produced a matrix with both the ears and the combination web of less thickness than that of its body, but 45 wherein both are located at the rear side of the matrix and in substantially the same plane. As a consequence of this construction, and particularly in connection with the customary distributing devices, I secure certain 50 valuable results, which proceed from the fact that the matrices may now be disengaged from their supporting means with their rear faces always in the same plane, irrespective of their thickness. A suitable

form of mechanism for handling such matrices is illustrated in my pending application for Letters Patent, Serial No. 733,586, filed November 26th, 1912, of which the present application is a division.

By the term "rear side," as herein employed, is meant that side of the matrix which during the travel of the latter through the distributing mechanism is the following one as distinguished from the leading one. In this connection, it must be remembered that sometimes, or at certain stages of the circulation of the matrix through the machine, it travels otherwise than with the above indicated side rearmost, for instance, during composition, when such side is the leading one instead of the following one.

Referring to the drawing: Figure 1 shows a matrix having my invention applied thereto; and Fig. 2 shows a matrix of the kind now in use.

Referring to Fig. 1, my improved matrix X is provided with the projecting ears X¹ and the distributing toothed combination X² formed in a thin web thereof, it being noted that the ears X¹ and combination X² are located at the rear side of the matrix and in the same plane, or in other words, at that side thereof which lies to the right of the formative character X³.

Fig. 2 illustrates the form of matrix Y now in general use, having the ears Y¹ and the distributing combination Y² at opposite sides thereof, it being noted that the ears Y¹ are located at the forward side or at that side which lies to the left of the formative character Y³. The matrix Y is also formed with a vertical recess Y⁴, which is designed to straddle the end of an overlying bar and thus permit the elevation of the matrix, when it is lifted into engagement with the distributor screws. The necessity for this recess is entirely dispensed with in my improved construction, and this feature constitutes one of its advantages.

I have shown my invention as applied to the particular form of matrix shown, but obviously it may be adapted to other forms as well without departure from its spirit.

Having thus described my invention, what I claim is:

1. A type or matrix adapted for circulation in a typographical machine, wherein it travels in one direction during composition

and in the opposite direction during distribution, the said type or matrix being formed with projecting ears of less thickness than that of its body, and the said ears being located at that side of the type or matrix which in its normal position is the leading one during composition and the following one during distribution.

2. A type or matrix adapted for circulation in a typographical machine, wherein it travels in one direction during composition and in the opposite direction during distribution, the said type or matrix being formed with projecting ears and a distributing combination, both of less thickness than that of its body and located in the same plane and at that side thereof which in its normal position is the leading one during composition and the following one during distribution.

3. A type or matrix adapted for circulation in a typographical machine, wherein it travels in one direction during composition and in the opposite direction during distribution, the said type or matrix being formed with projecting ears of less thickness than that of its body and located at that side of the type or matrix which in its normal position is the leading one during composition and the following one during distribution, and the said ears having one of their faces lying in the same plane as the aforesaid side or face of the type or matrix.

In testimony whereof I have affixed my signature in presence of two witnesses.

JOHN R. ROGERS.
